UNITED STATES PATENT OFFICE

101,103

DESIGN FOR A TOY VEHICLE OR THE LIKE

Ralph W. Brooks, Los Angeles, Calif.

Application September 23, 1935, Serial No. 58,665

Term of patent 14 years

To all whom it may concern:

Be it known that I, Ralph W. Brooks, a citizen of the United States, residing at Los Angeles, in the county of Los Angeles, State of California, have invented a new, original, and ornamental Design for Toy Vehicles or the like, of which the following is a specification, reference being had to the accompanying drawing, forming part thereof.

The figure is a perspective view of a toy vehicle, showing my design.

I claim:

The ornamental design for a toy vehicle or the like, substantially as shown.

RALPH W. BROOKS.
